CUSHIONED HEEL

George W. Griffith, Norwalk, Conn.

Application October 24, 1935, Serial No. 46,464

4 Claims. (Cl. 36—35)

This invention relates to improved heels for shoes, particularly to cushioned and pneumatic cushioned type heels.

Most cushion heels are secured to shoes with 5 nails of other spur like members and a problem is involved to prevent the heel from pulling free from the nails, especially since the material of the heel is usually made of yielding rubber. In general there have been two proposals in the 10 past to overcome this difficulty.

One proposal, and the one now used most generally, was to mold metal washers in the rubber heel, said washers having inner holes smaller than the head of the nail to prevent the 15 rubber heel from pulling over the nails. However, such heels are costly to produce because usually seven separate washers are provided and the seven washers must be placed, one after another on suitable shaped supporting elements in the die. Therefore, production is low and cost 20 high. Also, there is the danger of the operator inadvertently forgetting to add the washers, or of inadvertently leaving them off in order to speed his production and increase his pay. The operator or molder can do the latter very easily 25 with comparative freedom from detection because the washers are hidden by the rubber heel molded therearound. In either event, if the washers are omitted, the efficiency of the heel is impaired.

The second and more recent proposal has been 30 to provide a substantially D-shaped insert of plywood laid upon the top of the cushion heel, adapted to allow the thin section of a nail or other stud to pierce or otherwise pass there- 35 through, but stopping the head section for the purpose of holding the heel to the shoe. However, such structure has the disadvantage of lessening the resiliency of the heel; e. g. the layer or top section of the heel is a solid un- 40 yielding member representing approximately 25 per cent of the entire heel thickness, thus ren- 45 dering the heel only 75 per cent, or less, effec- tive than a rubber heel of the same height with- out the wooden insert. Although it does not occur frequently, the rubber part of such a heel structure can be pulled from the wooden insert because the latter is not backed by the rubber of the heel—the wood insert itself is clamped or nailed directly to the heel.

It is an object of the present invention to over- 50 come the disadvantages of these two previous proposals which are now in general use. To this end the present invention provides a heel struc- ture with only one insert, rather than seven as is 55 usual, which is capable of flexing or yielding

with the usual flexing of the rubber section of the heel, but which is still capable of preventing the head of studs from passing therethrough, or of the rubber heel being pulled from the studs which are secured to a shoe.

In practically all previous proposals, some 5 holes were provided in the insert or inserts necessitating a slow and careful move of aligning these holes with pins in the molding die, and other like factors which slowed up the amount of production, and increased the manufacturing cost.

It is an object of the present invention to provide a cushion heel having an insert or like structure adapted to more effectively secure the cushion heel to the shoe, which can be made in very 15 large quantity economically.

A feature resulting from the accomplishment 20 of this object includes a single insert without holes which may be easily and quickly dropped onto a stepped section of the die and secured in 25 place by molding at the time that the cushion heel is formed.

A complementary feature is the provision of a 30 one piece insert spaced both from the top and the bottom of the heel, backed up substantially by a molded section of the cushion heel so that the insert cannot be pulled from the rubber. There is now a growing preference among users 35 of cushioned heels for the so-called pneumatic cushion type of heel, with an air chamber, similar to that disclosed in my Patent No. 1,951,975, issued March 20, 1934. However, the solid plywood form of heel section hereinbefore described does not permit the molding of an air chamber and if used would reduce the air chamber to such 40 a degree as to seriously impair its value.

It is an important object of the present invention to provide a pneumatic cushion type heel with only a single insert adapted to receive a plurality of studs, with the one insert serving to hold the rubber heel to the studs and to the shoe.

Even though a single wooden or like insert is used to advantageously hold the heel to the shoe according to the provision of this invention, it is sufficiently flexible so that it does not impair the general resiliency and efficiency of the heel, and it therefore provides a very advantageous heel structure.

Other objects, features, and advantages will appear hereinafter.

In the drawing:

Figure 1 is a top plan view of a rubber heel according to the present invention.

Fig. 2 is a bottom plan view of the heel shown in Fig. 1.

Fig. 3 is a side sectional view of the heel, taken on line 3—3 of Fig. 1.

5 Fig. 4 is a sectional view taken on line 4—4 in Fig. 2.

Fig. 5 is a top plan view of a slightly modified form of the present invention.

10 Fig. 6 is a sectional view of that form of the invention shown in Fig. 5 and taken on line 6—6 of the latter figure.

Fig. 7 is a top plan view of another modified form of the present invention.

15 Fig. 8 is a sectional view of that form of the invention shown in Fig. 7, and taken on line 8—8 of Fig. 7.

Fig. 9 is a perspective detail view of the insert.

20 Referring now in detail to the drawing which shows the present preferred embodiments of the invention, description of that form shown in Figs. 1 through 4 and 9 is given first.

25 As illustrated in this drawing, there is provided a heel 12 having an integral bottom 14, and marginal edge 15', the latter including an outer wall 15 and front wall 16. These parts are preferably molded integral, of rubber or similar resilient material. The bottom 14 and walls 15 and 16 form a large substantially D-shaped cavity or air chamber 28 therein to form a pneumatic 30 chamber with a vent 17 in order to collect and expel air, as set forth fully in my aforesaid patent.

35 Now, of particular importance, the present invention provides a substantially U-shaped insert 18, most fully shown in Fig. 9, of ply wood or the like. This insert rests upon a stepped wall 19 within the outer wall 15, as may be seen best in Figs. 3 and 4, and is held thereon by a series 40 of integral lugs 20 projecting inwardly from the outer wall 15.

45 These lugs 20 hold the insert 18 onto the stepped wall 19 and also prevent the insert 18 from being pulled away from the molded and resilient rubber.

50 Small depressions 22 may be provided on an outer face 23 to indicate where nails are to be started in order to pass substantially through the middle of the lugs 20 and insert 18 to secure the heel to a shoe.

55 It will be understood that small screws, barbs, spurs, and any other suitable stud may be used instead of a nail. The small depression 22 may also be in the form of a hole extending down to the insert within the rubber heel and coextensive with a hole 24, as shown in Fig. 9. However, such a construction is deemed less advantageous than one without holes.

60 As shown, the point of the stud is located by the slight depression 22 and then is driven right down into the rubber. The pointed part of the stud is driven through the insert 18, its travel being stopped when a usual head thereon engages with an underside 25 of the insert 18. A plurality of nails, seven as shown, serve to very effectively secure the heel to the shoe and the insert effectively prevents separation of the heel 12 from the studs.

65 It should be particularly noted that recesses 26 are provided between each of the lugs 20 directly above the insert 18. These cavities provide a two-fold advantage. At the time of molding, sections 26' on the insert 18 underlying the recesses 26 rest directly upon a step in the mold to be thoroughly supported thereby during the molding operation. It will be readily appreciated,

70 without disclosing molding dies, that an inner wall 27 of the insert may be hooked upon the male member of the die which forms the chamber 28 while the sections 26' rest upon a shoulder section of such a male member to space and support the insert relative to the bottom face 23 and to a top face 29 of the heel at the time of molding. This represents a real advantage at the time of molding and makes possible high quantity production and economical manufacturing 10 cost.

75 Another advantage made possible by the recesses 26 is the fact that sections of the insert 18 are not backed up or are left unsupported so that sections 26' of the insert 18 between the studs 20 15 may yield readily. Thus, it is possible to obtain considerable resiliency in the heel even though a piece insert 18 of wood or the like is used.

80 Although the insert 18 may be provided with with an interconnecting front section 30, as shown by dot and dash lines in Fig. 9, molded into or adjacent the front wall 16 to form a substantially D-shaped member, it is preferably made U-shaped. By leaving ends 31 and 32 free, as shown by solid lines in Fig. 9, the heel 25 may have a certain amount of sidewise movement, viz., straight pressure may be translated into side pressure and the free ends of the insert will permit yielding to the side.

85 The stepped wall 19 makes possible a deeper 30 pneumatic chamber 28 and a more remote placement of insert 18 relative to the bottom wall 14 and face 23. Any type of configuration or design 34 may be molded upon the face 23. It will be appreciated that the insert 18 will bow 35 as a person steps onto the back of the heel, and that there will be a general flexing of various parts of the insert 18 concurrently with the flexing of various parts of the heel.

90 Figures 5 and 6 show a modified form of the 40 present invention which is the same as the preferred form just described in detail in all particulars except that the stepped wall 19 is eliminated and the width of the insert is increased so that a section thereof is molded into 45 the side wall 15 as shown at 37 in Fig. 6 and by a dotted line 38 in Fig. 5. In heavier shoes where it is desired to secure the heel in place with large studs, there may be danger of splitting the narrow width insert 18 of the preferred 50 form. An insert of greater width therefore has the advantage of reducing the possibility of splitting when studs are driven in place. Recesses 26 between the lugs 20 with sections 26' 55 may also be provided with this form of the invention for the advantages already outlined. Such a heavier duty heel would preferably be less resilient than the preferred form set forth. Accordingly, the center section 39 would be filled with rubber to the top 40 of the insert 18'. 60

95 Figs. 7 and 8 show a further modified form of the present invention wherein the insert 18 is fully molded in place. This may be effected by molding approximately half of the rubber heel so that the insert 18 will be partly exposed to be located and supported, for example, while the bottom half is molded, and subsequently molding the remainder of the heel while at the same time covering or substantially covering all of the insert.

70 One advantage of this last form of the invention is that it is not necessary to add the holding studs in a limited number of predetermined places. If preferred, the outer face 23 may be provided with a channel 41 generally indicated 75

5 by lines 42 in Fig. 2 extending in a U-shape about the configuration 34 and substantially midway of the sides and below the insert 18. This form of the invention also shows a cross rib 43 joining adjacent side walls 44 to prevent adverse spreading.

10 All three forms disclosed show chambers 28, 28a, and 28b, and all have vents 17, 17a, and 17b respectively, showing novel insert structure of the present invention with pneumatic cushioned heels. A duct 17c may be provided in a bottom 15 46 passing through the cross rib 43.

15 Although the inserts 18 and 18' are shown as made of three ply wood, it should be understood that they may be made equally well from fibre, pressed wood, and other compositions. These inserts may be sawed or punched from 20 ply wood and like strip materials, or may be molded from suitable materials. Pressed wood, of the type made from sawdust and held together by a suitable binder has been found very satisfactory for this purpose since it is quite 25 resilient, will not split when a nail or stud is driven therethrough, and may be provided in any desired shape very economically.

25 Other modifications may be made within the scope of the present invention and portions of the invention may be used without others.

Having thus described the invention, what is 30 claimed as new is:

1. A rubber heel comprising a body having a cavity therein; a nail receiving insert; a bottom wall; a stepped wall supporting said insert, said insert and said stepped wall defining sides.

of said cavity; and portions of said rubber body overlying said insert to prevent the latter being pulled away from said body.

2. A rubber heel comprising a body having an air chamber and having a top and bottom face; a marginal edge defining said chamber; a vent for said air chamber; a solid insert of material more rigid than rubber carried by said marginal edge intermediate the top and bottom face of said heel body, adapted to flex and thereby 10 allow the air chamber and vent to function efficiently; and lugs with intervening recesses overlying said insert.

3. A rubber heel for shoes comprising a body member, having cavity therein; a bottom wall; 15 an outer wall; a front wall; a stepped wall within the outer wall; a nail receiving insert supported on said stepped wall, said insert and stepped wall defining sides of said cavity; and rubber lugs overlying said insert to prevent 20 the latter being pulled away from said body.

4. A rubber heel comprising a body having a substantial cavity in the upper face thereof constituting an air chamber; a side wall; a bottom wall; an upwardly extending central 25 portion of said bottom wall spaced from said side wall and forming the bottom of said cavity; a nail receiving insert located in the space intermediate the side wall and the upwardly extending central portion; and portions on said 30 side wall extending inwardly to overlie said insert to prevent the latter being pulled away from said body.

GEORGE W. GRIFFITH.
